UNITED STATES PATENT OFFICE.

CHARLES SPIRO, OF NEW YORK, N. Y.

TYPE-WRITING MACHINE.

SPECIFICATION forming part of Letters Patent No. 322,495, dated July 21, 1885.

Application filed January 6, 1885. (No model.)

To all whom it may concern:

Be it known that I, CHARLES SPIRO, a citizen of the United States, residing at New York, in the county of New York, and State 5 of New York, have invented certain new and useful Improvements in Type-Writers, of which the following is a specification, reference being had to the accompanying drawings.

This invention has relation to that class of 10 type-writing machines which involve in their construction a longitudinally movable type-sleeve bearing printing characters or surfaces—such as letters, numerals, and punctuation-marks—a series of keys, one for each printing-character, and connecting mechanism, whereby motion imparted to the keys is communicated to the type-sleeve in order to bring 15 a printing-character thereon corresponding with that of the key operated to a common 20 printing-point, so that with suitable mechanism for carrying the paper to be printed upon along, and by said common printing-point, printed matter may be produced by the machine.

25 Among the objects of my invention are to reduce the number of parts, the simplification of the individual parts and of the machine as an entirety, the compact arrangement of the several operative elements of the machine in 30 order to reduce its size, the exposure of the letters and words printed at the time of and after the printing of the same without moving any portion of the machine, the capability of the substitution of different styles or forms 35 of printing-characters, the provision of variable spacing adapted to the requirements of any style of printing-characters, and means whereby complete words may be printed by the single operation of a single key, the operation 40 of the paper-feeding devices by the gravity of the paper-carriage, and the provision of such a construction as will permit the substitution of carriages of differing lengths, and the co-operation of the same with the rest of 45 the machine, whereby it is adapted for use in printing matter desired to be expanded to any length of line.

50 Other objects and advantages of my invention will appear in the following description, and the novel features thereof will be specifically pointed out in the claims.

Referring to the drawings, Figure 1 is a per-

spective of a type-writing machine constructed in accordance with my invention. Fig. 2 is a plan of the same with the keys removed. 55 Fig. 3 is a similar view with the keys, their levers and guiding and supporting mechanism removed. Fig. 4 is a bottom view in plan of the machine. Fig. 5 is a front elevation and Fig. 6 is an end elevation of the machine. Fig. 7 60 is a skeleton perspective of the operating-lever and certain devices co-operating therewith. Fig. 8 is a front elevation of the feeding mechanism, portions being shown in section. Figs. 9, 10, 11, 12, and 13 are details, hereinafter 65 described.

Like letters indicate like parts in all the figures.

All of the operative parts of my machine are connected with or arranged upon or beneath a single base-plate or bed, A, which is supported by any suitable standards, as A'. For the purpose of describing the construction of the machine herein illustrated as one embodiment of my invention, I designate as 75 the front of the machine the side opposite that at which the carriage is placed, the front being the side toward the operator, the general height of the machine being such that an unobstructed sight of the work produced upon 80 the paper while upon the carriage can be had at the time of and subsequently to the printing of the same.

Upon the base A, and near the corners thereof, are four posts or standards, A², which serve to support rods A^{2*}, on which the key-levers B are pivotally mounted. Between the posts A², and parallel with the rods mounted in them, are arranged two partitions, A³, which are slotted through and through, as at 90 A⁴, to permit of the passage therethrough of a portion of a key-lever nearest its pivoted end and grooved, as at A⁵, to receive the free end of the key-lever, which is pivoted on the bar at the opposite end of the machine from 95 said groove. One-half of the levers are pivoted at one side of the machine, and the other half at the opposite side thereof, the levers crossing each other at about the center of the machine, their free ends riding in the 100 grooves A⁶ in the inner surfaces of one of the partitions A³. Springs A⁶ are secured in any suitable manner to the partitions, and project so as to bear against the under side or edge of

each of the key-levers for the purpose of returning the same to a normal position after having been depressed.

At a suitable point along the upper edge of each of the key-levers B is arranged a rod or standard, B', which bears the key proper, B², the faces of which are also to bear as usual the character which is brought to the printing-point by depression of the key. Each of the key-levers B is projected from its pivot at a right angle to its main portion, as at B³, and the projection is provided with an adjusting-screw, B⁴, for a purpose hereinafter described.

Pivoted connected to the standards A², at either side of the machine, and extending completely along and beneath the entire series of keys pivoted at each end of the machine, are the bails B⁵, which, by a spring hereinafter described, are normally maintained in an elevated position—that is, bearing against the under edges of the key-levers B, so that as each key of each half of the series of levers is depressed one of said levers depresses the bail at that side of the machine at which one-half of the levers are pivoted.

From each of the bails B⁵ there passes through the bed-plate A a rod, B⁶, the lower end of which abuts against the upper surface of the rock-arms B⁷, projecting from a rock-shaft, B⁸, supported in brackets B⁹, formed on or secured to the under surface of the bed-plate. Projecting to the rear, and rigidly mounted on the rock-shaft B⁸, is another rock-arm, B¹⁰, the extreme rear end of which is resilient or yielding. In this instance this characteristic of that portion of the rock-arm B¹⁰ is secured in the provision of a curved flat spring, B¹¹, attached by screws B¹² (or it may be in any other manner which will suggest it to any skilled mechanic) to the rigid portion B¹⁰ of the rock-arm. By reference to Fig. 4 it will be seen that in this instance brackets A⁷ are secured to the bed-plate and project therefrom in a plane substantially parallel with and lower than its main portion, and at the rear ends of these brackets are standards A⁸.

By reference to Figs. 2, 3, and 6 it will be seen that the paper-roll and the carriage for the same are mounted in ways formed in a carriage-supporting part, A⁹, which I shall for convenience designate as the "platen-frame." At each end of the platen A⁹, arms A¹⁰ are extended and pivoted in the standards A⁸, so that the platen-frame, the carriage, and the paper-roll thereof are adapted for a rising and falling motion.

From the center of the platen-frame, and projecting toward the front of the machine, is a lug, A¹¹, which is provided with an adjusting-screw, A¹², and set-nut A¹³. Immediately over the lug A¹¹ is a pivoted check-lever, pawl, or stop, A¹⁴, provided with a similar adjusting-screw and nut, A¹⁵. The stop A¹⁴ is mounted in a depending bracket or lug, A¹⁶, formed on or secured to the under surface of the bed-plate.

As thus far described it will be seen that when any one of the keys is depressed its lever is brought into contact with the upper surface of one or the other of the bails B⁵, so that the movement of the key-lever is by said bail communicated by means of the rods B⁶ to the rock-arms B⁷ and B¹⁰ of the rock-shaft B⁸, depressing the arms B⁷ and elevating the free end of the arm B¹⁰, the rigid portion of said arm acting directly to withdraw the stop A¹⁴ from contact with the upper surface of the lug A¹¹, which contact acts to retain the platen-frame A⁹ in a depressed position, resting upon the screw A¹⁷, mounted in the bracket A⁷, while by reason of the curved surface A¹⁸ of said stop suitable movement of the rigid portion of the arm B¹⁰ is permitted before the stop is released from the lug. During this limited movement of the rigid portion of the arm B¹⁰ power is being stored in the spring B¹¹, or, in other words, the tension of said spring against the adjusting-screw A¹² is being constantly increased, so that at the instant that the stop A¹⁴ is removed from contact with the lug A¹¹ the power thus stored, or the tension of the spring thus increased, serves to suddenly lift the platen-frame with the carriage and paper-roll thereon, and to force the paper-roll and the paper thereon quickly and firmly against the characters on that face of the type-sleeve which is presented toward the paper, the recoil of the blow and the weight of the paper-roll, the carriage, and the platen-frame all serving to bring it back to its normal position, the adjusting-screw A¹⁷ being set at such a point that the stop A¹⁴ shall by gravity resume its normal position above the lug A¹¹.

By the construction and operation thus far described each depression of each of the keys is utilized to give a necessary motion to a proper part of the machine to secure the impression of a printing-character upon the paper. It now remains to describe the devices and construction employed in this my invention for selecting the character to be printed, and for feeding the carriage to present the proper surface of the paper to receive the character when printed.

The first principal element necessary to accomplish the purposes just stated is the type-sleeve D, the construction, character, manner of mounting, and the devices employed for the operation of which will now be described.

The type-sleeve is a square, or it may be a polygonal tube, the inner bore of which may be either square, round, or polygonal, and is mounted upon a rotatable rod, D', adapted to the bore of the tube. In case a cylindrical rod, D', is employed a spline or fin, D², is used to prevent the rotation of the sleeve upon the rod, and in case the rod D' is square, polygonal, or triangular portions of its faces may be removed, as shown at D³, to reduce the friction of the sleeve upon the rod and the extent of the surface which requires finishing to fit the bore of the sleeve. The type-strips D⁴ may be soldered directly to the outer faces of

the sleeve or may be otherwise secured thereto; but for the purpose of making provision for the use of different styles of type I prefer to form in the outer surfaces of the sleeve longitudinal dovetail grooves D^5 , and to correspondingly shape the edges of the type-strips D^6 , as shown at D^6 . One or more faces of the sleeve, or one or more removable type-strips, may be provided with complete words, as shown in Fig. 3, or two styles of type may be formed on a single strip, if desired; but I prefer to arrange in transverse lines upon the strip or the sleeve a printing character or characters and projections or depressions D^7 to determine the spacing required by said characters, as hereinafter described. The rod or shaft D' is in this instance mounted in brackets D^8 , extending rearwardly from the base-plate A , and in a bracket, D^9 , arranged upon said plate. The rear end of the rod and a portion near its front end is adapted to be rotated in the brackets D^8 D^9 , while at its extreme front end it is provided with a thumb-nut, D^{10} , and a notched disk, D^{11} , into which the spring-actuated detent D^{12} takes, the notches being so arranged on the disk with relation to the faces of the sleeve as to present one or the other of said faces toward the carriage when the detent is in a notch. The presentation of desired faces of the type-sleeve for use is in this instance accomplished entirely by hand, as described.

The devices employed for the longitudinal reciprocation of the type-sleeve upon the rod D' , so as to bring any character upon a lower face thereof to a common printing-point, comprises bell-crank levers E , pivoted at E' to the base A and connected by links E^2 to a collar, E^3 , formed in two parts, which are adapted to embrace a circular bearing, D^{13} , formed in the sleeve D , the pivots E^4 of the links serving also to bind the two parts of the collar within the bearing D^{13} . From the front end of the type-sleeve, and secured to and formed as a part of, or it may be secured to the upper half of the collar E^3 , is projected a bracket, the end of which is turned vertically to form a stop, D^{14} .

The means for operating the levers E are clearly shown in Fig. 1. Upon the rod A^{2*} , mounted in the standards A^2 , which serves as the pivotal bearing for the key-levers B , is a bail, F , having a depending arm, F' , which is adapted to be brought into contact with the shorter arms of the levers E . From the bail F there depends a spring-plate, F^2 , against which the adjusting-screws B^3 of the key-levers B abut when a key is depressed, so that motion is conveyed to the arm or rod F' , and by it and its companion on the opposite side of the machine to the levers E , links E^2 , collar E^3 , and sleeve D , so as to project the sleeve along the rod D' from front to rear. To determine the extent of the reciprocation of the sleeve and movement of the lever E , each of the adjusting-screws B^3 is so set as to give the required movement to the spring-plate F^2 , bail F , and arm F' .

Now, the arrangement of the characters upon each face of the printing-sleeve is such that those most frequently used will be nearest to the printing-point when the sleeve is in its normal position, and the relative arrangement of the key-levers one with another is such that each shall, when depressed, form an obstacle to the further advancement of the sleeve when it is reached by the key-lever in its downward movement. The function of the spring-plate F^2 now becomes apparent, in that, by means of the adjusting-screws B^3 , the pressure exerted upon the plate by the shorter arms of the key-levers is regulated, so that the movement of said arms of the levers occurring in bringing the lever into contact with the stop D^{14} , shall be just sufficiently absorbed by the spring-plate to regulate the extent of the movement of the arm F' against the lever E , so that the sleeve shall be reciprocated in proportion to the location of the type thereon. In other words, by means of a yielding connecting element, and suitable adjusting devices between the pivots of the key-levers and those of the sleeve-reciprocating levers, I am enabled to distribute the force exerted in depressing any single key of the entire series and its lever to the sleeve, so that the sleeve shall receive just a sufficient quantity of that force to carry it only to the lever which is depressed.

The single stop D^{14} upon the sleeve is sufficient for ordinary purposes; but in more rapid writing I prefer to employ two stops, as illustrated in Fig. 9, the rear one, D^{14*} , being lower than the front one, and the rear lower corner, B^* , of the lever B being beveled or removed, so that as the lever B is brought into contact with the rear surface of the higher stop, D^{14} , allowance is made for the passage of the rear stop, D^{14*} , completely beneath the lever, and for exceedingly slight reaction and a final complete entrance of the lever between the two stops, which are situated at such a distance apart that the lever clearly retains the sleeve from movement in either direction when the lever is depressed to its lowest point.

I consider the construction of these parts as possessing novelty and great advantages in practical use.

A coiled spring, E^5 , is connected with each of the levers E , for the purpose of returning the sleeve to its normal position after having been once operated by the levers.

It now remains to describe the construction and operation of the carriage-feeding devices, and in this portion of the machine other of the important novel features of my invention are embodied. As heretofore described, the carriage G is mounted for longitudinal movement in or on the platen A^9 , which is supported pivotally, so as to rise and fall during the operation of printing. The carriage is provided with the usual bearings for the paper-roll G' , a thumb-nut, G^2 , and a ratchet, G^3 , being provided, as usual, for the rotation of the paper-roll for line to line movement. Paper-retaining de-

5 devices G^4 , of usual construction, are also provided. A rack-bar, G^5 , is formed along the front side of the frame-work of the carriage, which frame-work or base is dovetailed into the 10 platen, as clearly shown. In this instance the carriage, as described, is completely separable from the platen, so that without disconnecting any of the devices from the machine a carriage may be removed therefrom, and another carriage, adapted to fit the platen and of any desired length, may be inserted therein for use in connection with the printing devices. By reason of this construction and adaptation to put in and take out carriages of differing lengths, 15 one machine may be employed for printing matter of usual or unusual length of line. A job partially done may be removed, and another carriage with a new job inserted without displacing the printing point of the job removed, and so that work may be readily resumed thereon, as occasion may require.

20 At the front side of the platen is a standard, H , to which is pivoted a bell-crank lever, H' , the pivot being at H^2 , near the top of the standard H . That arm of the lever H' which depends over the rack-bar G^5 is projected at each side, and provided at the front in the line of feed, during the process of printing, with a pivoted spring-pressed feed-pawl, H^3 , 25 the spring I of which is rigidly secured to the depending portion of the lever H . The rear projection of the lever H is provided with a detent, H^4 . The pawl H^3 is extended in rear of its pivot, as at H^5 , which extension is rounded on its upper surface. The free upper end of the lever H' comes in contact with a relatively-fixed projection (in this instance a portion, J' , of the spacing-lever J) when said lever is in its normal position.

30 As hereinbefore more particularly set forth, the platen will be raised after the pivoted stop A^{14} has been removed from the upper surface of the lug A^{11} (formed on or secured to the platen) by means of the increased tension produced in the spring B^{11} . In the act of rising the platen elevates the standard H secured to it, and this in turn elevates the pivot H^2 of the lever H' , and if means are provided to retain the free end of said lever in contact with 35 a relatively-fixed point, as J' , the detent H^4 will be raised from the rack G^5 and the pawl H^3 will be carried backward over the teeth of said rack, and over such a number of the teeth as may be desired, by controlling the pawl 40 against the resistance or pressure of the spring I for a greater or less length of time during its backward movement. Now, the means provided for retaining the free end of the lever H' in contact with the fixed point J' may 45 be an increased weight of that portion of the lever to counterbalance the other portions of the lever and its adjuncts at the other side of its pivot, or a coiled spring, as H^6 , may be employed to keep the free end of the lever in 50 contact with the point J' of the spacing-lever J . The spring J^2 maintains the spacing-lever J in an elevated or normal position, and the

50 standard J^3 carries a key, J^4 , for said lever, which key may be arranged in any suitable convenient proximity to the system of keys 70 employed in the machine.

To determine the number of teeth over which the feed-pawl shall pass in its backward movement when the platen is raised, and therefore to determine the distance that the carriage with the paper thereon shall be conveyed after each impression, and to do this automatically, I provide a standard, K , mounted upon the bed of the machine, therefore independent of the platen and carriage, and pivot thereon a bell-crank lever, K' , the pivot being shown at K^2 . One arm of this lever is provided with a pin or projection passing beneath the lever H' , as at K^3 , which pin is connected with said lever by means of a spring, K^4 , so that the tendency of said arm and pin shall be to remain in contact with the lever H' . The other arm of said lever K is provided with an adjusting-screw, K^5 , which is adapted to bear upon the spacing projections or depressions D^3 of the type-sleeve, so that as these projections or depressions vary in height or depth the lever K shall be oscillated on its pivot, so that the pin or projection K^3 shall be removed from the lever H' and the portion bearing the adjusting-screw K^5 shall be oscillated more or less to the rearward in the line of feed. In order to utilize this variation in the oscillation of the lever K , (which variation it will be seen will be in accordance with the spacing required to print any given character on the sleeve,) I secure to the lever a wire, K^6 , (or, the lever itself may be so extended,) so shaped as to pass downwardly and around the standard H and lever H' to and above the rearward projection, H^5 , of the feed-pawl, as shown at K^6 .

55 Now, it is apparent that at the time of the raising of the platen and the return of the lever H' in the manner described, and of a simultaneous return of the lever K , as described, that the wire K^6 will act to retain the pawl for a longer or a shorter time from returning to the rack G^5 , when a key and all of the connecting devices between it and the spring B^{11} , which holds the platen up, are released, and the consequent falling of the platen occurs. In this manner the spacing depressions or projections upon the type-sleeve determine the amount of feed required for the character or the word 60 upon the sleeve adjacent to said projection or depression which is printed by the sleeve. The force exerted on a key accomplishes the following results in substantially the following order: A key-lever is depressed, the sleeve reciprocated to expose a certain character or word and its spacing projection or depression at the printing-point, the spacing-lever K is set for the required feed, and the platen is raised to give the impression.

65 The inking device employed in this instance comprises any ink absorbing or retaining roller, L , mounted upon the shaft L' and removably retained thereon by means of the nut

L^2 , said shaft being supported in a yielding bearing or spring, L^3 , secured to the under side of the bed A, so that as the sleeve is reciprocated upon the rod D' the characters thereon come in contact, before reaching the printing-point, with the roller L.

It is apparent that many of the minor details of my invention may readily be changed by persons skilled in the art of manufacturing type-writers, and I therefore do not limit my invention to the exact details of construction herein shown and described, but reserve my right to alter the same in any manner and to any extent within the skill of the class of persons mentioned.

By means of the key J^4 and the spacing-lever J, upon which it is mounted, independent spacing or feeding of the carriage may be accomplished, as desired, the point J' of the spacing-lever being lowered in order that the spring H^6 of the feed-pawl lever may lower the free end of said lever and carry the pawl backward on the rack G^5 .

The spring-plate F^2 permits the completion of the downstroke of the key-levers after they have come in contact with the stop D'^4 , which limits the forward reciprocation of the type-sleeve D. The key-lever during the latter part of its downward motion, acting upon the bails B^5 and rods B^6 , serves to operate the rigid and yielding portions of the rock-arm, which liberates and elevates the platen to take an impression. Without the yielding element between the ends of the key-levers and the sleeve-reciprocating levers, the contact of the stop of the type sleeve with the key-lever would be so positive and forcible as to occasion a rebound in the type-sleeve, which would result in blurred impressions, as well as subjecting the machine to severe wear in operation.

Having described my invention and its operation, what I claim as new is—

1. In a type-writing machine, the combination, with a reciprocating type-sleeve having a stop of a system of key-levers arranged across the path of the same, and connections, substantially as described, for operating the sleeve.

2. In a type-writing machine, the combination, with a reciprocating type-sleeve having a stop and with type-sleeve reciprocating levers, of a system of key-levers arranged across the path of the sleeve, each of which levers is provided with a key bearing an indication of the type or character which is brought to the printing-point when said lever is depressed, and a connecting device which is partly rigid and partly resilient, substantially as specified.

3. In a type-writing machine, the combination, with a reciprocating type-sleeve having a stop, of a system of key-levers, a portion of which are pivoted at each side of the sleeve and connected with duplicate type-sleeve operating-levers, substantially as specified.

4. In a type-writing machine, the combina-

tion, with a type-sleeve having a stop, of a series of key-levers arranged across the path of the sleeve, a bail arranged beneath the levers and connected with a rock-shaft, an arm of which is partly rigid and partly resilient, a pivoted platen connected with the yielding portion of said arm, a pivoted locking-pawl connected with the rigid portion of said arm, and a carriage mounted upon the platen, substantially as specified.

5. In a type-writing machine, the means shown and described for taking an impression from the printing-characters thereof, said means consisting of a pivoted or movable platen-frame, a carriage or paper-carrier, a lever operated by means of printing-character selecting-keys, and having a rigid and a resilient portion, the former connected with a stop for temporarily retaining the platen from rising to take the impression, substantially as specified.

6. In a type-writing machine, the combination, with platen-frame and paper-carrier, of a lever having rigid and resilient portions, a movable stop, and devices, substantially as described, for operating the lever, substantially as specified.

7. In a type-writing machine, the combination of a reciprocating type-sleeve and type-sleeve operating-levers with a system of key-levers having adjusting-screws, a bail having a spring-plate, and a type-sleeve lever-operating rod, substantially as specified.

8. In a type-writing machine, the combination of a pivoted platen-frame having a feed-pawl carrying standard, a paper-carrier provided with a rack, a feed-pawl lever having a bearing at its free end upon a fixed portion of the machine, and devices, substantially as described, for raising the platen-frame, substantially as specified, whereby the platen-frame in the act of falling operates the feed-pawl.

9. In a type-writing machine, a carriage and feed-rack, a rising and falling platen-frame provided with a feed-pawl and standard, a feed-pawl lever pivoted to the standard and projecting over a fixed part of the machine, in combination with adjustable devices, substantially as specified, for regulating the spacing.

10. In a type-writing machine, the combination, with a reciprocating type-sleeve having a front and rear stop, the latter being lower than the former, of a key-lever arranged across the path of the sleeve and constructed to enter and fill the space between the stops thereon, and connections for operating the sleeve, substantially as specified.

11. A type-sleeve for a type-writing machine provided with printing-characters and spacing-projections, substantially as specified.

12. A type-strip for a type-writing machine provided with printing-characters and spacing-projections arranged in transverse lines upon the same, substantially as specified.

13. In a type-writing machine, the combination of a reciprocating type-sleeve, its operating-levers, a rising and falling platen-frame

and a paper-carrier thereon, feeding devices mounted upon the platen-frame, and devices substantially as described, for varying the extent of the feed, mounted independently 5 of the platen-frame, substantially as specified.

14. In a type-writing machine, a rising and falling platen-frame, a paper-carrier mounted thereon and provided with a rack, feed devices mounted on the platen-frame, and an independent lever mounted on the fixed part of 10 the machine for independent operation of the feed devices, substantially as specified.

15. In a type-writing machine, the combination, with a carriage, a rising and falling platen-frame having a rack, and the feed-pawl, of a 15 variable spacing-lever and devices, substantially as described, for regulating the action of the lever upon the pawl, substantially as specified.

16. In a type-writing machine, the combination of a feed-pawl pivotally mounted on a 20

bell-crank lever, a pawl-operating spring, a detent, an independently-mounted variable spacing-lever projected above the pawl, devices, substantially as described, for regulating the operation of the spacing-lever, and an independent hand-spacing or feed lever, substantially as specified. 25

17. In a type-writing machine, the combination, with key-levers and a type-sleeve-operating devices, of a partly-rigid and partly-resilient lever for absorbing a portion of the motion of the key-levers before the sleeve-operating devices are made to act, substantially as specified. 30

In testimony whereof I affix my signature in presence of two witnesses. 35

CHARLES SPIRO.
